UNITED STATES PATENT OFFICE.

JOHN B. SEMPLE, OF SEWICKLEY, PENNSYLVANIA.

SELECTIVELY-ACTING FUSE.

1,347,716.

Specification of Letters Patent. Patented July 27, 1920.

Application filed October 16, 1919. Serial No. 331,087.

To all whom it may concern:

Be it known that I, JOHN B. SEMPLE, residing at Sewickley, in the county of Allegheny and State of Pennsylvania, a citizen 5 of the United States, have invented or discovered certain new and useful Improvements in Selectively-Acting Fuses, of which improvements the following is a specification.

10 My invention relates to improvements in fuses for shells, and consists in a selectively acting fuse: that is to say, a fuse which, in case the shell makes impact upon a body of relatively small resistance to penetration, 15 functions to effect bursting quickly, but which, in case the shell makes impact upon a body of great resistance to penetration, such as heavy armor plate, will function with relative slowness.

20 The accompanying drawing shows in longitudinal section a fuse embodying my invention.

In this drawing the fuse stock is indicated at 1, and is, as will be seen, adapted to be 25 screwed into an opening in the base of a shell. This stock is provided within with an anvil block 2 and a hammer block 3 adapted to move, one relatively to the other, in a runway which extends longitudinally 30 of the structure. In this instance it is the hammer block which alone is movable, and it takes the familiar form of a plunger equipped with a firing-pin. A shear-pin 4 is provided, normally holding the movable 35 member against movement; but the shear-pin is relatively weak, so that, under the tremendous shock of firing, the movable member first sets back, under inertia, shearing the pin in so doing and releasing itself, 40 and then, when subsequently the shell makes impact, the movable member will drive forward, under inertia, and explode the percussion cap. A spring 5 is effective, to prevent the movable member, when once it is 45 released, from moving forward until under the great and sudden retardation which occurs on impact, the movable member lunges forward with great relative momentum, compressing the spring as it goes, and striking and firing the percussion cap. All this 50 is well known in the art.

My present invention has to do with the communication of ignition from the percussion cap, through the block which lies between, and to the burster charge. The block 55 is in this case the anvil block 2; but, in this

connection, it will be borne in mind that anvil and hammer members may be reversed in position if desired, as already intimated, and as is known to the art. Communication 60 is direct through block 2 to the burster charge.

There are through block 2 two lines 65 through which ignition may be communicated; one of these is the flashway 6-7; the other is the canal 6-8, in the course of which is set a pellet 9 of slow-burning material, such as is commonly used in time fuses. If ignition passes through the flashway 6-7, the action of the fuse is quick, and 70 bursting follows at a minimum time interval after impact; if on the other hand ignition is through canal 6-8, then the pellet 9 of slow-burning material must be burned through before ignition can reach the burster 75 charge, and this will be accomplished only after an appreciable time interval following impact. The length of this time interval (in any case very short, of course) may be varied, increased or decreased, according to 80 the composition of pellet 9, the degree of its compression in manufacture, and its length. A duct 18 affords escape for gases generated by the burning of pellet 9.

It remains now to explain how the fuse is 85 rendered selective, to the end that on impact upon a body offering relatively small resistance to penetration, ignition is through flashway 6-7, and on impact upon a body offering relatively great resistance to penetration, ignition is through canal 6-8.

In the course of the flashway 6-7 is a 90 chamber 10, with a plug 11 in it, constituting a movable cut-off for the flashway. This plug is formed of rigid material—steel, for 95 example, and is imperforate. Normally, this plug is in the retracted position shown, leaving the flashway unobstructed, and is held in this position by a shear-pin 12. It will be observed, first, that the plug is normally secured at the posterior end of its range of movement, accordingly there is no shearing strain upon pin 12 when the shell is fired from a gun. (There is such strain on shear-pin 4.) Shear-pin 12 is relatively 100 strong, to the end that relatively small arrest of flight, due to impact on light plate, e. g., will not effect shearing, but only extreme strain such as occurs by sudden and great arrest of flight, as when the shell 110 makes impact on heavy armor, will effect shearing. When pin 12 is thus sheared, plug

- 11 sets forward to obstruct flashway 6-7. It will be observed that as shown in the drawings the distance through which plug 11 advances to close the flashway is very much less than that through which plunger 3 advances to fire the percussion cap, and it is of the essence of the invention that the plug 11 when it functions shall in closing the flashway anticipate the flash.
- 10 The canal 6-8 through which delayed ignition may be effected is always in operative condition, and ignition proceeds along that line; but, as will now be well understood, in case the percussion cap is fired without operation of cut-off plug 11 (which will happen on impact upon relatively light resistance), the progress of ignition through canal 6-8 will be anticipated by the flash which travels directly through flashway 6-7 to effect quick firing of the burster charge. On the other hand, if impact upon heavy armor has caused plug 11 to close the flashway before the percussion cap is fired, then the only remaining line of ignition is through delay pellet 9, and so the fuse has become a delay-action fuse.
- 17 is a "booster" charge, intermediate in

position and in function, between percussion cap and burster charge; it is fired by the flash from the cap and it in turn imparts 30 detonation to the burster charge beyond. It is a member of the assembly already well known in many forms to the art; and in and of itself it constitutes no part of my present invention.

35

I claim as my invention:

A selectively acting fuse for a projectile including a block in which are formed two paths of ignition transmission from percussion cap to burster charge, one of said 40 paths being a quick-action and the other a delay-action path, a rigid imperforate plug, under all lesser strains immovable and aside from either path of ignition transmission, but under the strain of impact upon 45 heavy armor movable within the block to a position of closure of said quick-action ignition path, substantially as described.

In testimony whereof I have hereunto set my hand.

JOHN B. SEMPLE.
